Des No 1886

Des. 1886

Elmer J. May, of Lowell, Mass.
Assign to

The Lowell Manufacturing Company.

Letters Patent No 1886 Dated Jan'y 19th 1886.

Design for a Carpet Pattern.

The schedule referred to in these Letters Patent and making part of the same.

To all whom it may concern:

Be it known that J. Elmer J. May, of Lowell, in the County of Middlesex and State of Massachusetts, have originated and designed a new pattern for carpets or other fabrics, of which the following is a full, clear and exact description, reference being had to the accompanying drawings, making part of this specification.

Fig. A, is a broad belt, composed of the narrow bands 1, 1, 1, 1, mottled work 2, 2, scalloped band 3, 3, and vines 4, 4.

Fig. B, is a belt similar to A, and runs parallel with it.

Fig. C, is a broad belt composed of the series of lace work 5, 5 and 6, 6, and runs at right angles with belts A and B, extending over A, and under B. Fig. D, is similar to A, the exception that it extends over B and under A.

Each of the before mentioned belts support a rope-like band, the extreme tips of the bands being connected at the sides and ends of the design, by small rosettes.

The rope-like bands support the rosettes 7, 8, 9, 10.

Extending from corner to corner diagonally across the design are two chains of blocks, crossing each other at right angles in the centre.

In the centre of the design are four groups of flowers, leaves and sprigs, and by matching the four corners four similar groups are formed.

The colors employed for the different portions of the design, may be varied to suit the taste and wish of the manufacturer.
